UNITED STATES PATENT OFFICE.

MORRIS P. BRAY, OF WORCESTER, MASSACHUSETTS.

DESIGN FOR THE ORNAMENTATION OF CORSETS.

SPECIFICATION forming part of Design No. 17,398, dated June 21, 1887.

Application filed April 4, 1887. Serial No. 233,657. Term of patent 14 years.

To all whom it may concern:

Be it known that I, MORRIS P. BRAY, of Worcester, in the county of Worcester and State of Massachusetts, have invented a new 5 Design for the Ornamentation of Corsets; and I do hereby declare the following, when taken in connection with accompanying drawing and the letters of reference marked thereon, to be a full, clear, and exact description of the 10 same, and which said drawing constitutes part of this specification and represents a side view of the corset.

This invention relates to a design for the ornamentation of the exterior surface of a corset; 15 and it consists in the configuration and ornamentation, as shown in the accompanying illustration. The lower edge of the corset is curved upward from the front to the hip line, and thence curved downward to the back. From 20 the busk or front section, A, is the representation of a band, B, presenting the appearance of a series of parallel ribs following the lower edge of the corset up to the front edge of the hip-section C. On the hip-section front of the central line is the representation of a series of parallel ribs, D, as running from the top downward 25 to the waist-line, thence curved toward the front; and at the rear of the central line of the hip-section is the representation of a series of 30 ribs, E, as running from the top of the corset down to the waist-line, thence curving rearward to the bottom of the corset; and on the rear section, F, of the corset is the representation of a vertical series of parallel ribs, G, running from 35 the top to the bottom of the corset. Between

the two series of ribs D E at the bottom of the corset is the representation of a gore, H, of inverted-V shape. Between the hip and the breast section is the representation of a series of parallel ribs, I, as running from the top of 40 the corset downward and as terminating at the top of the band.

I claim—

The herein described design for the ornamentation of a corset, consisting in the representation of a band, B, on the lower edge of the corset, following the lower edge from the front to the front edge of the hip section and presenting a series of ribs parallel with the bottom of the corset, the representation of a vertical 45 series of ribs, I, on the front section as running from the top of the corset downward and as terminating at said band B, the hip section representing two series of parallel ribs, D E, extending from top to bottom, one series in 50 front of and the other in rear of the vertical central line of the section, and the said two series represented as diverging from about the hip-line downward, the representation of a vertical V-shaped gore, H, between said two 55 series of ribs, D E, at the bottom of the hip section, and with the representation of a vertical series of parallel ribs, G, on the rear section as running from top to bottom of the corset, as 60 shown in the accompanying illustration.

MORRIS P. BRAY.
